United States Patent Office.

J. H. SEYMOUR, OF HAGERSTOWN, MARYLAND.

Letters Patent No. 74,610, dated February 18, 1868.

IMPROVED SPITTOON FOR CARS.

The Schedule referred to in these Letters Patent and making part of the same.

TO ALL WHOM IT MAY CONCERN:

Be it known that I, J. H. SEYMOUR, of Hagerstown, in the county of Washington, and State of Maryland, have invented certain new and useful Improvements in Spittoons for Cars, &c.; and I do hereby declare that the following is a full, clear, and exact description of the same, reference being had to the accompanying drawings, making a portion of this specification, in which—

Figure 1 is a vertical transverse section of a spittoon made according to my invention.

Figure 2 is a plan view of the same.

Similar letters of reference indicate corresponding parts in both figures.

This invention is designed more particularly for use in cars having double bottoms, and may be considered as an improvement on the inventions set forth in my Letters Patent, numbered 54,613 and 59,280 respectively, and it consists in a funnel-shaped shell, so combined with the spittoon and the bottom of the car as to prevent the shavings or similar filling ordinarily employed to deaden sound in the car-bottom from interfering with the proper operation of the valve of the spittoon when the latter is used.

The invention further consists in a novel means whereby the choking of the outlet-neck of the spittoon from the partial freezing of the material that may accumulate therein, is effectually provided against.

To enable others to understand the nature and construction of my invention, I will proceed to describe it with reference to the drawings.

A and A* indicate the upper and lower portions of the double floor of a car, the space between such portions being ordinarily filled with shavings or equivalent material to deaden sound upon the floor. Fitted into and extending through this floor is a funnel-shaped shell, B, to the lower end of which is attached the conducting-pipe shown in red outline in fig. 1, which serves to convey away the matter or material passing from the spittoon. The spittoon is shown at C, and should, for the most part, be of conical form, as represented in fig. 1, and is suspended within the shell B by means of a flanch, a*, provided upon its upper edge or circumference, and resting upon the upper portion of the floor at the top of the shell, as shown in the figure just mentioned. The spittoon C has formed at its lower end the neck a, which is slightly conical in shape, being widest at its lower end. Pivoted at one side of this neck, at the bottom thereof, is a valve, b, which is provided with a downwardly-extending arm, b*, to which is pivoted the lower end of a sliding piece or bar, D, which extends through a slot, a', in the shell, and an opening, b', in the upper part of the floor, and has formed at its upper end a curved surface, c'. The lid or cover C* of the spittoon works upon a vertical pivot, c*, in such manner that it may be turned laterally to open or close the spittoon. As the cover C* is turned aside to uncover the spittoon, it acts upon the surface c' of the sliding piece D, and, forcing the same downward, causes it to turn the valve b upward against the end of the neck, thus closing the same, as shown in the drawings, and when the cover is moved inward to close the spittoon, it is brought away from the surface c' of the sliding piece D, which being released, enables the valve b to fall by its own weight, as indicated in red outline in fig. 1, opening the neck a, and permitting the substances therein to fall down into the shell B, and thence into the conducting-pipe connected therewith.

Inasmuch as the shell extends considerably below the spittoon, ample room for the movement of the valve b is afforded, and as the shell effectually separates the spittoon from the filling between the two portions of the floor, it follows that such filling cannot in any way interfere with the just herein-described operation of the valve. Furthermore, the neck a, being longest at its lower end, any retention of the substances situated therein, or, in other words, upon the valve, when the latter is in position to close the neck, which would otherwise occur in case such substances should become partially frozen, is very securely provided against, the substances dropping freely from the neck, instead of adhering to the sides thereof.

What I claim as my invention, and desire to secure by Letters Patent, is—

1. The combination of the conical shell B with the spittoon C and the bottom A A*, substantially as and for the purpose specified.
2. The neck a, made with its interior of conical form, and largest at its lower end, arranged at the bottom of the spittoon C, and in relation with the valve b, substantially as and for the purpose specified.

J. H. SEYMOUR.
